UNITED STATES PATENT OFFICE

2,417,335

BOBBY PIN

Lloyd R. Westby, Berwyn, Ill.

Application May 26, 1945, Serial No. 595,970

5 Claims. (Cl. 132—46)

1

This invention relates to hair pins and more especially to those hair pins commonly known as bobby pins, and its principal object is to improve on the construction and operation of articles of this character.

Bobby pins are usually made from resilient material, such as narrow steel strips bent upon themselves approximately midway between their ends to provide two clamping fingers which are urged together by the resilient action of the U-bend of the pin.

One of the objects of this invention is to utilize the spring action in the U-bend to separate the fingers whereby the fingers may be more easily and readily separated in order that the pin may be conveniently applied to a tuft of hair or to a curl.

Another object is the provision of a catch or shouldered tongue struck up from one of the fingers of the bobby pin and arranged to engage the other finger and releasably hold the two fingers in clamping engagement with a tuft of hair or a curl.

Another object is to provide such a catch or shouldered tongue which will automatically snap into holding engagement when the two fingers of the bobby pin are brought together.

With these and other objects and advantages in view, this invention consists in the several novel features hereinafter fully set forth and more particularly defined in the appended claims.

The invention is clearly illustrated in the drawing accompanying this specification, in which:

Fig. 1 is an enlarged side elevation of a bobby pin partly broken out and illustrating a simple form of the invention;

Fig. 2 is a plan thereof, and

Fig. 3 is a perspective view of the bobby pin.

Referring to said drawing, which is merely illustrative of one embodiment of the invention, the reference character 5 designates a strip of resilient material, such as a narrow spring steel strip bent upon itself approximately midway between its ends to form a U-bend 6 from which extend two hair clamping fingers 7, 8 arranged one above the other. The fingers 7, 8 are generally parallel throughout their greater extent, but the finger 7 is bowed outwardly from the U-bend, as at 9, and this bowed portion extends to the other finger 8 (when the fingers are closed upon each other) at which point the finger 7 is formed with a reverse bend 10 which contacts with the finger 8 and from the reverse bend 10, the finger 7 extends approximately parallel with the finger 8 to the end thereof, but slightly spaced there-

2

from and at the end the finger is formed with an inwardly bowed portion 11 which engages with the finger 8.

5 The inherent spring tension in the U-bend functions to spread the fingers apart somewhat, as is indicated by the dotted lines in Fig. 1.

Struck up from the finger 8 at a point below the bowed portion 9 of the finger 7 is a catch or shouldered tongue 12 which extends toward the bowed part 9, and when the two fingers are closed upon each other the catch or shouldered tongue latchingly engages the finger 7 and releasably holds the two fingers in clamping condition.

10 The catch is formed with a shoulder 13 at its free end which is arranged to hook upon the other finger.

15 In the form of the invention illustrated, the bowed portion 9 of the finger 7 is formed with a slot 14 therein through which the shouldered end 20 of the catch may extend with the shoulder engaging the bowed portion of the finger adjacent the slot.

To separate the fingers preparatory to clamping a tuft of hair or a curl with the bobby pin, 25 the catch is pressed back, out of engagement with the finger 7, whereupon the spring tension of the U-bend spreads the fingers apart somewhat. The user can then spread the fingers farther apart if necessary and apply the bobby pin to a 30 tuft of hair or to a curl and then by pressing down upon the outwardly bowed part 9 of the finger 7, the fingers are brought together and clamped upon the tuft of hair or the curl, the catch snapping into locking engagement with the finger 7 and thereby positively holding the fingers in clamping engagement upon the hair.

35 To detach the bobby pin from the hair, the catch is pressed back detaching it from the finger 7, whereupon the U-bend spreads the fingers apart somewhat and the bobby pin may then be readily withdrawn from the tuft of hair or the curl.

40 As is common in bobby pins, the fingers may be straight or slightly bowed or they may be kinked, 45 in accordance with the common practice.

45 Among some of the advantages which result 50 from the bobby pin above described are that the fingers can be opened, applied to a tuft of hair or a curl and snapped shut upon the tuft of hair or the curl. The bobby pin can be used and reused indefinitely. It has more holding surface because of its peculiar construction. It can be opened before removing it from the tuft of hair or the curl. It has greater spring strength in the 55 U-bend. It holds the curl more firmly and is easy

to operate. It snaps and unsnaps from the bowed end only, which eliminates the necessity of providing latching means at the free ends to lock or unlock the fingers. The snap catch eliminates the possibility of ruining the spring tension in opening the fingers.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A bobby pin comprising a single length of resilient material bent upon itself approximately midway between its ends to provide a U-bend from which extend two fingers having substantially parallel overlying portions, one of which has an outwardly bowed portion merging into the U-bend and a resilient catch struck up from one of the fingers below the bowed portion and arranged to extend through a slot in the bowed portion to releasably hold the two fingers in clamping position.

2. A bobby pin comprising a single length of resilient material bent upon itself approximately midway between its ends to provide a U-bend from which extend two fingers one overlying the other, one of which has an outwardly bowed portion merging into the U-bend and a resilient catch struck up from one of the fingers below the bowed portion and arranged to extend through a slot in the bowed portion and having a shoulder to latchingly engage said bowed portion whereby to releasably hold the two fingers in clamping position.

3. A bobby pin comprising a single length of resilient material bent upon itself approximately midway between its ends to provide a U-bend from which extend two clamping fingers having parallel overlying portions, one of said fingers having an outwardly bowed portion merging into the U-bend and being formed with a slot, and the other finger having a resilient catch struck up therefrom and having a shoulder arranged to latchingly engage the opposite finger through the

slot whereby to hold the second finger in clamping position, said shoulder terminating in an inclined end portion which is arranged to engage an end edge of the slot to spring the shoulder into engagement with said edge when the bowed portion is pressed toward the opposite finger.

4. A bobby pin comprising a single length of resilient material bent upon itself approximately midway between its ends to form a U-bend from which extend two clamping fingers that are yieldably held in spaced apart relation by said U-bend, one of said fingers having an outwardly bowed portion merging into the U-bend and the other of said fingers having a resilient catch struck up therefrom below the bowed portion and having a shoulder arranged to extend through a slot in the bowed portion and latchingly engage said bowed portion whereby to hold the fingers in clamping position.

5. A bobby pin comprising a single length of resilient material bent upon itself approximately midway between its ends to form a U-bend from which extend two clamping fingers that are yieldably held in spaced apart relation by said U-bend, one of said fingers having an outwardly bowed portion merging at one end into the U-bend and merging at its other end into a reverse bend from which extends a portion substantially parallel with the other finger in the clamping position of the fingers and terminating in a bowed portion, bowed in the direction of the other finger, said reverse bend and last mentioned bowed portion functioning to hold the parallel portions of the fingers in a slightly spaced relation.
